UNITED STATES PATENT OFFICE

2,142,423

CONTROL FOR AIR CONDITIONING APPARATUS

William Walter Timmis, Glen Cove, N. Y., assignor to American Radiator Company, New York, N. Y., a corporation of New Jersey

Application September 4, 1936, Serial No. 99,367

1 Claim. (Cl. 236—44)

My invention relates to air conditioning means for houses or other buildings, and the object is to provide a simple, reliable and efficient system which is capable of being readily controlled to vary the character of the operation thereof.

Further, said invention has for its object to provide a system of the character specified, in which electrical circuits for controlling or actuating several air conditioning instrumentalities employed in the system will be under manual control for controlling the operation of one or more of said instrumentalities.

Further, said invention has for its object to provide a system of the character specified in which the air circulating means thereof may be operated either conjointly with a humidifying means thereof or independently thereof.

Further, said invention has for its object to provide a system of the character specified in which the air circulating means and the humidifying means thereof, or the air circulating means alone, may be operated either under control of a temperature responsive device or not, as required.

Other objects will in part be obvious and in part be pointed out hereinafter.

In the accompanying drawing, Figure 1 is a vertical, diagrammatic section of one form of system constructed according to and embodying my said invention, and

Fig. 2 is a wiring diagram thereof.

Referring to the drawing, the unit 10 of the particular air conditioning system disclosed, is of the type supplementing the usual heating system employed in a house or building, and includes an outer casing 11 having a return portion or duct 12 from the room or rooms of the building, and also in communication with the fresh air from the outside of the building. The air delivered through the portion 12 to the unit 10 first passes through a suitable filter 13, preferably composed of corrugated fibre board arranged to form V-shaped cellular passages for causing abrupt change in the direction of travel of the air. The surfaces of the fibre board are coated with a tacky compound for catching dust, soot, pollen, etc., carried by the air.

The air is forced or drawn through the casing 11 and into the supply pipe or outlet 14 for delivery to the room or rooms by air circulating means 15, preferably comprising a centrifugal type of blower driven by an electric motor 16. The blower 15 is preferably located within an inner casing 15a, while the motor 16 is mounted within the casing 11 below the supply outlet 14.

An air heating element 17 is located within

the casing 11 between the blower casing 15a and a second inner casing 18 forming a humidifying or spray chamber 19 immediately in advance of the filter 13. The heating means 17 preferably comprises the cast-iron headers 20 communicating with each other through the usual intervening heat radiating member made up of tubes (not shown) disposed transversely of the unit. Suitable operating fluid, such as steam or hot water, is supplied to the element 17 through supply pipe 21 connected to the upper portion of the header at one side, and the fluid escapes through the return pipe 22 connected to the lower portion of the header at the opposite side. The structure of element 17 forms no part of my present invention and therefore need not be shown or described in greater detail.

Water is delivered through a supply pipe 23 and is discharged into the humidifying chamber 19 through a spray nozzle 24 which ejects the water in a fine stream which impinges upon the target or plate 25 to produce a mist for the humidification of the air passing through the chamber 19. The nozzle 24 is preferably of the self-cleaning type. The supply of water to the nozzle 24 is controlled by means of a magnetic or solenoid shut-off valve 26 in the supply pipe 23. In operation, the air is drawn by the blower 15 through the filter 13 into the chamber 19 for admixing with the moisture therein, then through the tempering or heating element 17 for thermally conditioning the air for comfort and for vaporizing the moisture carried thereby, and thence through the blower to the supply outlet 14 for delivery to the rooms. A drain outlet 27 is provided for the removal of excess water which might be deposited within the unit 10.

The operation of the unit 10 may be flexibly controlled manually from the switch panel or plate 28 placed in a convenient location within the building and provided with the switch buttons or handles 29, 30 and 31 for controlling the circuits of the several instrumentalities or devices embodied in the unit.

Preferably, the system is also automatically controlled by the heat responsive circuit controlling device 32, preferably in thermal contact with the return pipe 22 at a point thereon close to the heating element 17. The heat responsive device is of any well known type adapted to make contact and close the circuit thereof upon rising temperature, and as the same attains a value of the order of 100°-200° F., according to the operating fluid employed.

The circuit through the thermostatic switch 32

includes the conductor 33 from the positive side of the line, switch 30, conductor 34 connected to one terminal of the thermostat 32, conductor 35 electrically connected at one end to the other terminal of the thermostat and at its opposite end 36 to the conductor 37 connecting the panel terminal 38 for the switch 29 with one of the terminals of the motor 16. The other terminal or side of the motor 16 is connected by the conductor 39 with the negative side of the line. The opposite panel terminal 38 of the switch 29 is connected by a lead 40 with the panel terminal 41^a of the switch 30 with which the conductor 33 is connected. The opposite panel terminal 41 of the switch 30 is for the attachment of the line conductor 33.

The terminal 38 is electrically connected by a bridging conductor 42 with the panel terminal 43 for the switch 31. The other terminal 43^a of the switch 31 is connected by conductor 44 with one terminal of a humidistat 45 adapted to automatically close the circuit thereof when the humidity drops to a predetermined value. The other terminal of the humidistat 45 is connected by conductor 46 which the positive side of the solenoid valve 26 controlling the water supply and operating when energized to open the valve. This allows one terminal of the solenoid valve 26 to be grounded, if so desired. The humidistat 45 may be located at any convenient point reflecting the humidity conditions such as in the room, or in the air return portion 12.

In operation, when it is desired to operate the unit 10 under automatic control, the switches 30 and 31 are closed and the switch 29 left open. With the switches 30 and 31 in closed position, the motor 16 is in series with the thermo-responsive device 32 and starts running as soon as the temperature of the heating element 17 or return 22 attains the desired value and the circuit at the thermostat 32 automatically closes. With the humidity control switch 31 closed, the thermo-responsive device 32 is also in series through the parallel circuit portion 37, connection 42, switch 31, and connection 44 with the humidistat 45 and the water controlling means 26.

With the switch setting as above described, the blower 15 cannot operate to draw air through the unit until the temperature conditions determined by the thermo-responsive device 32 and required for desirable operation are attained. Further, the electrically operated valve 26 is also under the control of the thermo-responsive circuit controlling device 32 and only operates when the circuit of the motor 16 closes to supply the nozzle 24 with water for the discharge thereof into the flowing air within the spray chamber 19. Such control is effective even though the humidistat 45 is calling for more moisture. If the switch 31 be opened the valve 26 closes and the fan 15 operates under the control of the thermostat 32 without the operation of the spraying device 24.

With the switches 29, 30 and 31 all closed, the fan 15 and spraying means 24 operate without control by the thermostat 32, the spray control 26 then being subject only to the humidistat 45, if the same is employed in the circuit. In this last control arrangement or setting the thermostat 32 is short-circuited, and the current is supplied from the positive side of the line through switch 30, conductor 40, switch 29, and conductor 37 to the motor 16 and then to the negative side of the line for insuring continuous operation of the blower 15. A parallel circuit is also then

completed through conductor 42, switch 31, humidistat 45 and control 26 to the negative side of the line for operation of the spray conjointly with the fan or blower. By opening switch 31, the fan or blower 15 may be operated alone without the operation of spraying means 24. By opening the main control or cut-off switch 30 the operation of the unit can be entirely discontinued, irrespective of the positions of the other switches 29 and 31.

By my invention I am able to operate the blower and spray conjointly, either under control of the thermostat 32 or not, as desired. In either case, the spray cannot operate unless the blower is operating, and the humidity control circuit may be manually opened without opening the circuit of the motor for operating the fan. The switch 30 is in series relation with both the fan operating circuit and the humidity control circuit, as well as with the respective switches 29 and 31 located therein, so that when the switch 30 is opened the operation of the motor 16 ceases and the valve 26 closes, even though the switches 29 and 31 remain closed. Irrespective of whether the motor circuit is closed through switch 30 or through both switches 29 and 30, the opening of the switch 31 will interrupt the operation of the spraying means without discontinuing the operation of the motor and the blower, and the flow of air through the system.

In my invention, the circuit connections are disposed so that the motor 16 and water control 26 in parallel relation may be placed either in series relation with said thermostatic control 32 or in short-circuited relation thereto, and I provide means for manually controlling said circuits to establish either of said relations as desired. I am also able by provision of a manual control in the parallel circuit portion including the humidity control 26 to operate the motor 16 and drive the blower 15 without operation of the humidifying means 24.

What I claim and desire to secure by Letters Patent of the United States is:—

In air conditioning apparatus for room spaces, the combination of a housing having an inlet and an outlet adapted to be connected to the space to be conditioned; means providing an air passage in said housing connecting the inlet and the outlet; a spray-type humidifier in said passage including a spray head; a solenoid valve controlling the flow of water to said head; a tubular heat exchanger arranged across said passage for heating the air leaving the humidifier; supply and return pipes for a heating fluid connected to said heat exchanger; a blower in said passage providing for the flow of air therethrough; an electric motor for operating said blower; a thermostat responsive to the temperature of the heating fluid at the return side of said heat exchanger; and an electrical circuit for operating said solenoid valve and fan motor selectively by hand and in response to said thermostat and comprising a main part including in series a master hand switch, said thermostat and two branch parts in parallel, one of said branch parts including said motor, and the other of said branch parts including in series a hand switch and said solenoid valve, and a shunt part connecting said master switch directly to said branch parts and shunting out said thermostat and including a hand operated switch.

WILLIAM WALTER TIMMIS.
